UNITED STATES PATENT OFFICE.

OTIS A. MYGATT, OF NEW YORK, N. Y.

DESIGN FOR A REFLECTOR OR SIMILAR ARTICLE.

No. 40,162.

Specification for Design.

Patented July 20, 1909.

Application filed May 16, 1907. Serial No. 374,107. Term of patent 14 years.

To all whom it may concern:

Be it known that I, OTIS A. MYGATT, a citizen of the United States, residing at New York, in the borough of Manhattan and State of New York, have invented a new, original, and ornamental Design for a Reflector or Similar Article, of which the following is a specification, reference being had to the accompanying drawing, forming part thereof.

The drawing is a side elevation of my design for a reflector or similar article.

I claim:

The ornamental design for a reflector or similar article substantially as shown.

OTIS A. MYGATT.
